CLAIM

The ornamental design for a protection cap for cylinder valve, as shown and described.

DESCRIPTION

1. Protection cap for cylinder valve

1.1 is a top, rear and left side perspective view.

1.2 is a top, front and right side perspective view.

1.3 is a front elevation view.

1.4 is a rear elevation view.

1.5 is a right side elevation view.

(Continued)

1.6 is a left side elevation view.

1.7 is a top plan view.

1.8 is a bottom plan view.

1 Claim, 8 Drawing Sheets
